UNITED STATES PATENT OFFICE

163,549

BUTTON GAUGE

Kenneth R. Wilson, Rock Lake Highlands, Wis.

Application April 20, 1950, Serial No. 9,369

Term of patent 14 years

(Cl. D52—1)

To all whom it may concern:

Be it known that I, Kenneth R. Wilson, a citizen of the United States, residing at Rock Lake Highlands in the county of Kenosha and State of Wisconsin, have invented a new, original, and ornamental Design for Button Gauge, of which the following is a specification, reference being had to the accompanying drawing, forming a part hereof.

Fig. 1 is a perspective view of a button gauge, showing my new design;

Fig. 2 is an end elevation thereof, showing the end at the right of Fig. 1; and

Fig. 3 is an end elevation showing the opposite end thereof.

I claim:

The ornamental design for a button gauge as shown.

KENNETH R. WILSON.
